(57) **CLAIM**

The ornamental design for a spray tip, as shown and described.

DESCRIPTION

FIG. 1 is a perspective view of a spray tip.

FIG. 2 is a right side view of the spray tip.

FIG. 3 is a left side view of the spray tip.

FIG. 4 is a front elevational view of the spray tip.

FIG. 5 is a rear elevational view of the spray tip.

FIG. 6 is a top plan view of the spray tip; and,

FIG. 7 is a bottom plan view of the spray tip.

The broken lines shown represent portions of a spray tip and form no part of the claimed design.
